UNITED STATES PATENT OFFICE.

ANTHONY COYNE AND LEE HASH, OF FORK RIDGE, TENNESSEE.

MINER'S LAMP.

1,344,867.

Specification of Letters Patent. Patented June 29, 1920.

Application filed April 19, 1917. Serial No. 163,149.

To all whom it may concern:

Be it known that we, ANTHONY COYNE and LEE HASH, citizens of the United States, residing at Fork Ridge, in the county of 5 Claiborne and State of Tennessee, have invented certain new and useful Improvements in Miners' Lamps; and we do hereby declare the following to be a full, clear, and exact description of the invention, such as 10 will enable others skilled in the art to which it appertains to make and use the same.

This invention relates to a new and improved lamp and more particularly to a lamp to be used by miners and the like when 15 working in mines, tunnels, sewers and like dark places where the operators are required to wear lights upon their hats or caps.

One of the aims of this invention is to provide a lamp provided with means for 20 generating a gas from carbide and water and provided with dual generating chambers and means so as to render the lamp capable of being inverted or reversed so that when one of the chambers has become 25 exhausted the other may be employed so that there is provided a continuous light and the miner or other workman will not be required to be in the dark when refilling the depleted chamber at any time before 30 the chamber then in use has become exhausted.

Another aim of this invention is to provide means for establishing intercommunication between the generating chambers so 35 that any excess gas will pass from one chamber to the other so as to equalize the pressure within the lamp and to also avoid any waste of the gas so that the gas can be subsequently utilized.

40 Another aim of this invention is to provide means for causing the water to be dripped upon the carbide drop by drop and which means is also adapted to be actuated in a manner for cleaning the water conduit 45 should the same become clogged or fouled from any cause, and to also provide means for the ready removal of the generating chambers for effectually cleaning the same of the slake carbide, and to also construct 50 all of the conduits, such as gas pipes and the like, in a manner that the same will be incased within the lamp so that the same will not be exposed at the exterior of the lamp and subjected to the danger of being

broken or otherwise injured by the lamp 55 coming into contact with surrounding obstructions and objects.

These and other objects and advantages will more fully appear as the nature of the invention is more clearly understood from 60 the construction, combination and arrangement of the parts thereof as fully described in the following specification, defined in the subject matter of the claim, and illustrated in the views in the accompanying drawings, 65 in which,

Figure 1 is a vertical sectional view, on line 1—1 of Fig. 2, showing certain of the detail construction of the lamp.

Fig. 2 is a detail vertical sectional view, 70 on line 2—2 of Fig. 1, showing a further detail construction of the lamp.

Referring to the drawings, wherein similar reference characters denote corresponding parts throughout the several views, 1 75 indicates one of the carbide chambers and 2 the other carbide chamber. These carbide chambers are open ended and are provided with exterior threads adjacent their open ends for threadingly engaging the respective internally threaded flange 3 and the internally threaded flange 4 upon the respective ends of the water tank or reservoir 5, whereby the carbide chambers 1 and 2 are oppositely disposed to each other with 80 85 their open ends facing each other and the water tank or reservoir 5 interposed therebetween.

Extending substantially centrally through the reservoir 5 and having its ends projecting for a distance beyond the side walls 6 and 7 of the reservoir 5 and into the respective carbide chambers 1 and 2 is the water conduit pipe 8 provided with the spaced valve bodies 9 and 10 for establishing a 90 communication between the interior of the reservoir 5 and the water conduit pipe 8, the passages through the valve bodies 9 and 10 being respectively controlled by the valves 11 and 12 provided with the valve 95 stems 13 and 14 formed with the threaded portions 15 and 16 which are threaded through the internally threaded bosses 17 and 18 upon one portion of the side wall of the reservoir 5, the projecting ends of 100 the valve stems 13 and 14 being provided with the angularly disposed operating handles 19 and 20, and diametrically opposite

the bosses 17 and 18 is the threaded nipple 21 through which the water is poured for filling the reservoir 5, the nipple 21 having threaded thereon the closure or cap 22.

5 In order to admit air into the reservoir 5 when the water therein is being used for the generation of gas, the air pipe 23 is provided and is positioned and secured upon the inner side of the side wall of the reservoir 5 at a point substantially midway between the bosses 17 and 18 and the filling nipple 21 and is open ended and extends from a point in proximity to the end wall 6 of the reservoir 5 to a point in proximity 10 to the end wall 7 of the reservoir 5, but at this point the end of the pipe is bent to provide the elbow 24, the end of which projects through the side wall of the reservoir 5 thereby establishing communication between the interior of the reservoir 5 and the outside atmosphere.

Extending through the reservoir 5 at one side of and preferably parallel with the water pipe 8 is the gas conducting pipe 25 having its ends suitably secured in the respective end walls 6 and 7 of the reservoir 5 and thereby establishing communication between the interior of the carbid chamber 1 and the interior of the carbid chamber 2, 25 and intersecting and having communication with the gas conducting pipe 25 is the laterally extending burner pipe 26 projecting through the side wall of the reservoir 5 at a point substantially diametrically opposite the air pipe 25 and provided upon its projecting end with the burner 27 and suitably secured upon the projecting end of the burner pipe 26 at the outer side of the side wall of the reservoir 5 is the reflector 28 30 surrounding the burner 27 and for reflecting the rays of light from the burner 27.

In order to cause the water from the reservoir 5 which is conducted through the water pipe 8 into the respective carbid chambers 1 and 2 to be deposited upon the carbid within the chambers 1 and 2 drop by drop there is projected through the water pipe 8 the rod 29 of a diameter sufficient to almost fill the opening through the pipe 8, 45 but not sufficiently so to prevent the water from passing through the pipe 8 to the chambers 1 and 2 in sufficient quantities for accomplishing the drop by drop result desired, and should the water pipe 8 become 50 fouled or clogged from any cause, the ends of the rod 29 which project outwardly of the ends of the water pipe 8 are provided with the laterally projecting curved ends 30 and 31 whereby the rod 29 may be rotated 55 within the water pipe 8 for cleaning the same and also reciprocated in a manner for removing the fouling or clogging material.

For efficiently attaching the lamp to the hat or cap of the workman there is provided 60 upon the outer side of the side wall of the

reservoir 5 and at a point substantially diametrically opposite the burner 27 the sleeve 32 having revolvably mounted therein the rod 33 having formed upon its opposite ends the sharp pointed hooks 34 and 35, the 70 pointed ends of which are directed inwardly toward each other but are disposed in planes substantially at right angles to each other, so that either the hook 34 may be swung outwardly for inserting in the hat or cap of the 75 workman when the lamp is in one position, or the hook 35 may be swung outwardly for inserting the same in the hat or cap of the workman when the lamp has been placed in its inverted or reverse position, and in either 80 instance the hook 34 or the hook 35, when the other is being employed, will lie flat against the outer surface of the wall of the reservoir 5. To prevent the lamp from swinging back and forth in a lateral direction when the same has been secured upon the hat or cap of the workman there is secured upon the sleeve 32 the transverse bar 36 which is preferably provided with angular pointed ends for sticking into the 90 leather or other band of the hat or cap of the workman.

The operation and advantages of the device will be briefly described as follows: Assuming the lamp to be secured upon the hat 95 or cap of the workman in the position shown in Figs. 1 and 2 with the carbid contained in the chambers 1 and 2 and the requisite quantity of water within the reservoir 5, the handle 20 of the valve stem 14 is now 100 rotated for opening the valve 12 whereby water will pass through the valve body 10 into the water pipe 8 and be dripped upon the carbid within the chamber 2 caused by the water trickling along the rod 29 and 105 dropping off the curved end 31, whereby gas will be generated within the chamber 2 and pass upwardly through the gas conducting pipe 25, through the burner pipe 26 and to the burner 27 which is now lighted, and should there be any excess of gas in the 110 chamber 2, the excess gas will pass onwardly through the gas conducting pipe 25 into the chamber 1, to be subsequently utilized as the same flows backwardly through the upper 115 portion of the pipe 25 to the burner 27 when the pressure has become somewhat diminished in the chamber 2 after the gaseous products of the carbid within the chamber 2 have been exhausted and before the light becomes 120 dim. The lamp is removed from the hat or cap of the workman by detaching the hook 34 therefrom and inverting the position of the lamp, the valve 12 being closed and the valve 11 opened by rotating its stem 13 125 through the medium of the handle 19, whereby the water from the reservoir 5 will now pass through the valve body 9 into the water pipe 8 and trickle down the rod 29 and drop from its curved end 30 upon the 130

carbid in the chamber 1, so that gas is now generated in the chamber 1 and passes outwardly through the gas pipe 25, the burner pipe 26 to the burner 27 for replenishing and supplying the flame of the burner 27. However, should there be any excess gas in the chamber 1 the same will pass through the conducting pipe 25 into the chamber 2. The lamp can now be used for double the 10 length of time that an ordinary lamp can be used and there is practically two lamps in one in this invention, and by causing the carbid chambers 1 and 2 to be in communication the pressure in the lamp is sufficiently 15 equalized and the danger of explosion reduced to a minimum. Furthermore, the chambers 1 and 2 are readily removable from the ends of the reservoir 5 and due to their shape, which is preferably semicircular, the same can be readily cleaned of the 20 slaked carbid and readily replenished with new carbid.

While there is shown and described only the use of one burner 27 and its connecting pipe 26, the lamp may be supplied with two or more such burners and pipes by duplicating the burners and connecting the same to the main gas conducting pipe 25.

Having described our invention, what we

claim as new and desire to secure by Letters Patent, is:—

An acetylene lamp comprising a water reservoir having opposite walls, a pair of opposite carbid chambers detachably secured to said walls, a tube connecting said walls and establishing communication between said chambers, a burner tube leading from said tube to the exterior, a water feed pipe connecting said walls, and having openings near its opposite ends adjacent to 40 said walls communicating with the water reservoir, valves for said openings having operating means extending to the exterior of the water reservoir, and an air vent for the water reservoir extending close to said 45 walls communicating at one end with the atmosphere near one of said walls and opening at its other end into the water reservoir near the other wall.

In testimony whereof we have signed our 50 names to this specification in the presence of two subscribing witnesses.

ANTHONY COYNE.
LEE HASH.
